SHAVING IMPLEMENT

Joseph Muro, Cambridge, Mass., assignor to
Gillette Safety Razor Company, Boston, Mass.,
a corporation of Delaware

Application April 29, 1936, Serial No. 76,999

4 Claims. (Cl. 30—42)

This invention relates to dry shaving implements and comprises a device organized to effect the cutting operation by nipping action as distinguished from the shearing action heretofore found in implements of this general type.

In implements operating upon a shearing principle it is necessary to interpose one of the shearing members between the face of the user and the point at which the hair is cut. However thin this member may be its presence renders close shaving difficult. On the other hand, the interposed shearing member acts to some extent as a gauge determining the minimum length of stubble. In the implement of my invention teeth are provided which are shaped to cut with a nipping action in a coincidental line which may thus be located at or substantially at the plane of contact with the face of the user. For example, the cutting teeth may be so shaped that the cutting edges lie substantially in the plane of their contact faces. In an implement with teeth of this character there is nothing whatever to gauge the length of stubble remaining uncut, but the teeth are guided so that they meet at the surface 25 of the skin and so pass lightly and without interruption over the face of the user without scraping or pulling. The resulting dry shave is, therefore, quicker and cleaner than that derived from the shaving implement operating on the shearing principle.

As herein shown each of two complementary members is provided with a series of spaced transversely extending teeth sharpened along their opposite top edges. The two members are assembled with their respective teeth alternately arranged and relatively movable from spaced relation in which hairs may enter freely between them, to nipping position in which the interposed hairs are either completely severed or so nearly as to break off. It is a fact that a hair notched on opposite sides to substantial depth will break off cleanly and that it is unnecessary that the nipper edges should actually meet in the hair.

Important features of the invention reside in the shape of the teeth which, as herein shown, are elongated transversely so that they each carry two cutting edges of substantial length, and are rounded at their ends so that they serve to direct the hairs into cutting position as the implement is moved transversely over the face. Preferably the teeth are also shaped so that they tend to lift the hairs into upright position as the latter pass between them.

The invention also includes as an important feature a novel two-way connection by which the movable member may be moved yieldingly in both directions of movement.

These and other features of the invention will be best understood and appreciated from the fol-

lowing description of a preferred embodiment thereof, selected for purposes of illustration and shown in the accompanying drawings, in which:

Fig. 1 is a plan view of the implement on an enlarged scale;

Fig. 2 is a view in side elevation, the casing being shown as broken away;

Fig. 3 is a cross-sectional view of so much of the implement as is shown in Fig. 2;

Fig. 4 is a fragmentary view in perspective on a still larger scale;

Fig. 5 is a view in perspective of the three principal parts of the implement shown in exploded relation;

Fig. 6 is a fragmentary view in cross-section showing a modified form of cutting tooth;

Fig. 7 is a corresponding view in elevation of the modified implement;

Fig. 8 is a fragmentary view in elevation of the implement, illustrating another modified form of cutting tooth; and

Fig. 9 is a view in cross-section on an enlarged scale of the construction shown in Fig. 8.

The implement comprises an elongated casing 25 which serves also as a handle and from the upper end of which project the operating instrumentalities. The upper end only of the casing is shown in Figs. 2 and 3 and within the body thereof is housed a small electric motor, not 30 shown, which is connected through an operating lever 11 to the movable tooth-carrying member 17 which will be presently described. By these means the movable member is maintained in a state of rapid vibration while the implement is 35 in use.

The stationary tooth-carrying member 13 comprises an elongated block provided in its upper face with a series of spaced transversely disposed cutting teeth 14. Each of these teeth, as shown 40 in Fig. 4, has a flat upper face with rounded ends and is under-cut in such a manner as to form sharp lateral cutting edges at each transverse marginal edge. The flat faces of the teeth 14 are designed to lie smoothly against the face of the user, while the rounded or tapered ends serve to deflect the hairs into the spaces between the teeth when the implement as a whole is moved transversely. The member 13 is provided upon its inner face with an intermediate rectangular 50 guide rib 15 and with a lower rectangular guide rib 16, the latter being interrupted by a centrally disposed opening.

The movable tooth-carrying member of the implement comprises an elongated block or slide 55 17 provided in its upper surface with a series of spaced transversely disposed teeth 18 formed similarly to the teeth 14 already described except that they are somewhat narrower. The teeth 18 are similarly flat faced and under-cut 60

to form lateral cutting edges at their opposite transverse edges and these edges are arranged in the same plane and coincidentally with the cutting edges of the teeth 14. When the two members 13 and 17 are assembled the rib 15 is received within a rectangular groove 19 provided for that purpose in the inner face of the slide member 17 and the lower face of this member engages the upper face of the rib 16, as shown in Fig. 3. In other words the two members are complementary in shape and the result of the interlocking engagement of the ribs and grooves is that the slide member 17 is guided for longitudinal movement with extreme accuracy in respect to the stationary member 13. The outer face of the rib 15 bottoms in the groove 19 and the transverse relation of the two parts is determined in this manner. The upper faces of the two series of teeth may be brought accurately into a common plane by grinding the two tooth-carrying members in their assembled relation. The slide 17 is provided in its lower edge with an opening 20 and through the opposite walls of this opening project the ends of a pair of spring plungers 21. The upper end of the operating lever 11 passes up through the central opening in the rib 16 and through the opening 20 in the lower edge of the slide member 17 and is provided with a rounded head which is engaged between the two opposed plungers 21, as best shown in Fig. 2. This construction affords one convenient two-way connection for imparting vibration to the slide member 17 in a yielding manner in both directions of movement.

The two tooth-carrying members 13 and 17 are maintained permanently in an assembled relation by an elongated clamping member 23 having an upwardly tapering side wall shaped to bear against the outer side of the slide member 17, as shown in Fig. 3 and having elongated relieved areas to reduce friction between the two. The clamping member has at each end a transverse arm 24 between which the slide member 17 may move endwise with ample clearance and which are secured to the ends of the stationary member 13 by pins 25. The three parts above-described are maintained in their assembled relation and are clamped in a socket formed in the upper end of the casing by a thumb screw 12 which is threaded through one wall of the casing and bears against the outer side of the clamping member 23.

When the two tooth-carrying members are assembled in operative relation as suggested in Fig. 4 they are guided so that the oppositely disposed cutting edges of adjacent teeth engage the opposite sides of an interposed hair in exact alignment nipping the hairs on both sides until it is finally cut-off. The oscillation of the operating lever 11 in one direction acting through one of the spring plungers 21 moves the slide to force one set of cutting edges into cutting relation and then acting through the other spring plunger 21 moves the slide to force the other set of cutting edges into operative relation. As shown in Fig. 2, for example, the operating lever 11 is acting upon the left-hand spring plunger 21 and has accordingly moved the slide member 17 of its extreme left-hand position in which the left-hand cutting edge of each tooth 16 coincides with the right-hand cutting edge of each tooth 14 of the stationary member. As shown in Fig. 4 on the other hand, the slide 17 has been moved to the limit of its stroke in the opposite direc-

tion. When the slide member 17 occupies either extreme position the open spaces between adjacent cutting edges is approximately .008 inch. This has been found a satisfactory opening freely to receive the hairs to be cut and as already noted, the rounded ends of the teeth tend to direct the hairs into the space between the teeth and their configuration is also such as to lift the hairs into upright position. It will be apparent that the implement may be moved in either direction across the face of the user and is equally efficient in either movement.

In Figs. 6 and 7 is illustrated modification of the invention in which the stationary teeth 54 are formed in an inverted U-shaped member 53 and the co-operating movable teeth 58 are formed in a second inverted U-shaped member 59 arranged co-axially within the member 53 and secured to the slide 55. The principal difference between the modifications of Fig. 6 and those already described is that the teeth in the former modification are supported at both ends, whereas the teeth of the implement as originally described are supported at one end and resemble in cross-section an inverted L. In all cases, however, the co-operating cutting edges or faces are arranged coincidentally to act upon the hairs to cut them off by a nipping action as distinguished from shearing.

In Figs. 8 and 9 is suggested a modification in which the teeth 38 of the movable member 37 are straight sided instead of being under-cut. In this case the hairs are nipped between the sharp transverse edges of the teeth 14 of the stationary member and the co-operating flat vertical face of the teeth 38 of the movable member.

In Fig. 8 the general contour of the cutting teeth is shown as being slightly convex instead of flat as in Fig. 4 but in this case the curvature of both series of co-operating teeth is identical so that the teeth make a curved line-to-line contact throughout their width.

Having thus described my invention what I claim as new and desire to secure by Letters Patent of the United States is:—

1. A shaving implement having relatively movable tooth-carrying members each equipped with a series of spaced teeth having their upper faces ground in a common plane, having rounded hair-directing ends and being shaped also to lift hairs into upright position as they enter the space between adjacent teeth.

2. A shaving implement having a stationary tooth-carrying member, a movable tooth-carrying member having oppositely directed spring plungers therein, and an operating lever engaged upon opposite sides by said plungers.

3. A shaving implement having relatively movable tooth-carrying members each equipped with teeth having their outer faces ground to lie in a common curve, the teeth of said members being alternately arranged and shaped to make curved line contact at their cutting edges.

4. A dry shaving implement comprising co-operating members, each having an elongated body portion with teeth projecting transversely from one side thereof and presenting oppositely directed nipping edges, said members being assembled side by side with the teeth of each member overhanging the body of the other, and means for relatively moving said members.
